UNITED STATES PATENT OFFICE.

FREDERICK A. HART, OF NEWARK, NEW JERSEY, ASSIGNOR TO UNDERWOOD COMPUTING MACHINE COMPANY, OF NEW YORK, N. Y., A CORPORATION OF NEW YORK.

TYPE-WRITING MACHINE.

1,293,091.

Specification of Letters Patent.

Patented Feb. 4, 1919.

Application filed July 6, 1917. Serial No. 178,885.

To all whom it may concern:

Be it known that I, FREDERICK A. HART, a citizen of the United States, residing in Newark, in the county of Essex and State of 5 New Jersey, have invented certain new and useful Improvements in Type-Writing Machines, of which the following is a specification.

This invention relates to an improvement 10 in typewriting machines, and more particularly to paper-fingers for assisting in maintaining a work-sheet properly on the platen.

The paper-fingers in the present invention are adjustably mounted on a fixed shaft, so 15 as to overhang the platen and coöperate therewith to guide and maintain the work-sheet smooth on the platen. The adjustment of the fingers on the fixed shaft is such, that when in a platen-engaging position, they 20 will be comparatively locked against accidental movement along the shaft. This is done by providing a collar splined on the shaft, having a spring connection with a sleeve, which in turn, is connected to an arm 25 bearing a pressure roll. The spring normally forces the roll into tight contact with the platen and reacts on the collar to cause it to bind on the shaft. A detent or lock is provided between the collar and the sleeve 30 to hold the arm and roll in an inactive raised position, at the same time taking up the tension of the spring and thus removing the binding friction on the shaft. In this relation of parts, the finger can be easily ad- 35 justed along the shaft.

Other features and advantages will hereinafter appear.

In the accompanying drawings,

Figure 1 is a perspective view, showing 40 the two fingers in their position engaging the platen.

Fig. 2 is a vertical section taken along the shaft and through the mounting for one of the fingers.

Fig. 3 is a top plan view of one finger, showing it locked in its raised inactive position.

Fig. 4 is a vertical section taken from front to rear, showing in full lines one of the 50 fingers in its active position, and in dotted lines the same finger in its raised and inactive position.

A platen 1 is secured to an axle 2, mounted in a frame 3. The frame 3 includes side

plates 4 and a paper apron 5, which latter 55 inclines downwardly from the rear to the bite of the platen and around the platen up to a line just short of the printing point. This printing point, indicated at 6, (Fig. 1), is where type-bars 7 strike the platen 1. The 60 paper apron 5 guides work-sheets around the platen and is assisted in maintaining the work-sheet on the platen by pressure feed rolls 8 and 9, indicated by dotted lines in Fig. 4.

To assist the paper apron 5 and the feed rolls 8 and 9 in properly maintaining the work-sheet on the platen 1, there are provided a pair of paper-fingers 10, which face inwardly toward each other, and when in 70 their active position, such as that illustrated in full lines in Figs. 1 and 4, engage the platen 1. For supporting the paper-fingers 10, there is provided a shaft 11 which is fixed in the side plates 4 of the platen frame 75 3, so that it will not rotate. This shaft 11 is provided with a slot 12 extending the full length thereof, whereby the fingers may be slid along the shaft 11 and controlled in their rotary position on the shaft. 80

Each of the fingers 10 includes a collar or sleeve 13 having a spring key 14 for securing it against rotation relative to the shaft 11 by engaging in the slot 12, but permitting a sliding movement along the shaft. The 85 collar 13 is provided with a head 15 secured rigidly thereto at one end, and a head 16 formed integrally thereon at the other end. Loosely mounted on the collar 13, there is provided a disk 17, which forms a part of 90 an arm 18, the latter being arched to conform to the cylindrical surface of the platen 1. The head 15 and the disk 17 are formed with rabbets forming hubs 19 and 20, respectively. 95

Secured to the disk 17 and the hub 20, and loosely mounted on the hub 19, there is provided a sleeve 21, which is of sufficient diameter to leave a space between its inner surface and the outer surface of the collar 13. In this space there is provided a coil spring 22, which is secured at one end to the head 15, and at the other end to the disk 17. In this way when the sleeve 21 is not locked to the collar 13 and the head 15, as described 100 below, spring 22 will tend to force the outer end of the arm 18 toward the platen 1. 105

To lock the arm 18 in a raised position, as

2

indicated in dotted lines (Fig. 4) against the tension of the spring 22, the head 15 is provided with a lug 23, which is arranged to engage in a socket 24 provided in the end 5 of the sleeve 21. Normally, this socket 24 is out of register with the lug 23, but can be brought into register therewith by raising the arm 18. When so raised, the tension of the spring 22 will draw the sleeve 21 and 10 parts carried thereby endwise along the collar 13, and force the socket 24 over the lug 23. In this way, the sleeve and the arm will be locked automatically when the arm is brought to its raised position. To enable 15 the spring 22 to act as a traction spring, as well as a torsion spring, its ends are secured to the head 15 and the disk 17 by being inserted in openings and turned over at its ends, as shown in Fig. 2.

20 The arm 18 in the case of each paper-finger 10, carries a stub shaft 25, which, for the right-hand paper-finger, projects to the left of the arm 18, and for the left-hand paper-finger, projects to the right of the 25 arm 18. This stub shaft 25 in each case bears a pressure roll 26, which is arranged to engage the surface of the platen 1 when the paper-finger is in its active position. The roll 26 in each instance extends through an 30 opening 27 in a spring metal guide 28, which is curved to conform somewhat to the surface of the platen 1 and extends down into close proximity to the upper front edge of the apron 5, as illustrated in Fig. 4, where 35 it presses against the platen 1. The lower edge of each of these guides 28 is turned upwardly at 29, so as to catch the leading edge of the work-sheet as it comes around the platen and cause the work-sheet to hug the 40 platen snugly. The guide 28 in each instance is secured to a pin 30 by having an upturned edge entering a slot 31 provided in the pin 30. The pin 30 in each instance, is secured to the arm 18, and the pins on 45 the two fingers project toward each other, similar to the stub shafts 25.

The utility of the device will be readily understood when taken in connection with the above description. When in use, the fingers 50 are in the position of Fig. 1, with the rolls 26 and the guides 28 in contact with the front surface of the platen 1. In this position they take the leading edge of the work-sheet as it comes around from the 55 apron 5 and hold the work-sheet snug on the platen at points above the printing point 6, thereby enabling clear and accurate type-writing. In this position, the springs 22 are normally under a tension and exert a certain 60 amount of pressure on the rolls 26 and the guides 28. This pressure reacts back on the collar 13, through the head 15 secured thereto, so that the collar will have rotated as far as it can, which is but very little, 65 causing the key 14 to grip one of the sides

of the slot 12, creating sufficient friction to prevent accidental sliding movement of the finger as a whole along the shaft 11.

When it is desired to throw the fingers out of use, it is merely necessary to raise 70 the arm 18 in each case, until the socket 24 comes into register with the lug 23. The spring 22 will then act as a traction spring, drawing the sleeve 21 and the parts carried thereby toward the head 15, causing the 75 socket 24 to seat itself on the lug 23. The lug and socket are so formed that they will not disengage accidentally from each other, and it will be necessary to positively force the sleeve 21 away from the head 15, in 80 order to again turn the sleeve 21 and the arm 18 relative to the collar 13 and the shaft 11. When, however, the arm 18 and the sleeve 21 have been turned to the raised 85 position of the arm 18 and locked in that position, the tension of the spring 22 will be taken up between the sleeve 21 and the collar 13. Then the tension of the spring will not tend to act on the shaft 11, so that each 90 finger can be readily slid along the shaft 11 90 without any trouble. In this way the fingers can be adjusted relatively to each other, so as to accommodate work-sheets of different widths.

Variations may be resorted to within the 95 scope of the invention, and portions of the improvements may be used without others.

Having thus described my invention, I claim:

1. The combination with a platen and a 100 frame in which it is rotatable, of a rod extending across said frame, a sleeve splined to said rod, an outer sleeve rotatable and axially slidable on said first-named sleeve, an arm including a paper-finger extending 105 from said outer sleeve, a spring between said sleeves normally tending to swing said arm against the platen, and a lug on one sleeve adapted to slide into a notch in the other sleeve by sliding the outer sleeve axially 110 when the finger is raised away from the platen, thereby locking the finger in its position away from the platen.

2. The combination with a platen and a 115 frame in which it is rotatably mounted, of a rod extending across said frame adjacent the platen, a sleeve slidably splined upon said rod, an outer sleeve axially slidable on said first-named sleeve, and including a collar by which it is carried by the first-named 120 sleeve, to provide an open space between the sleeves, means on the first sleeve adapted to prevent the outer sleeve from slipping off the first sleeve, a second collar on the first sleeve, including a rabbet on which the outer sleeve slides, an arm extending from the outer sleeve forming a paper-finger to lie against the platen, a lug on one sleeve adapted to slide into a notch on the other sleeve 125 by sliding the outer sleeve axially when the 130

finger is raised away from the platen, thereby locking the finger clear of the platen, and a spring lying between said sleeves effective to draw the lug and notch to engaging position.

3. The combination with a platen and a frame in which it is rotatable, of a rod extending across said frame, a sleeve splined to said rod, an outer sleeve rotatable and 10 axially slid able on said first-named sleeve, an arm including a paper-finger extending from said outer sleeve, a spring coiled on the first-named sleeve and lying within the outer sleeve normally tending to swing said 15 arm against the platen, and a lug on one sleeve adapted to slide into a notch in the other sleeve by sliding the outer sleeve axially when the finger is raised away from the platen, thereby locking the finger in its 20 position away from the platen.

4. The combination with a platen and a frame in which it is rotatably mounted, of a rod extending across said frame adjacent the platen, a sleeve slidably splined upon 25 said rod, an outer sleeve axially slid able on

said first-named sleeve, and including a collar by which it is carried on the first-named sleeve to provide an open space between the sleeves, a collar on the first-named sleeve adapted to prevent the outer sleeve from 30 slipping off the first sleeve, a second collar on the first sleeve, including a rabbet on which the outer sleeve slides, an arm extending from the outer sleeve forming a paper-finger to lie against the platen, a lug 35 on one sleeve adapted to slide into a notch in the other sleeve by sliding the outer sleeve axially when the finger is raised away from the platen, thereby locking the finger clear of the platen, and a spring coiled on the 40 first sleeve between its collars and lying within the outer sleeve, adapted to draw the lug and notch to engaging position, and also adapted, when the lug is free from the notch, to draw the finger against the platen.
